UNITED STATES PATENT OFFICE.

ELDON W. EBY, OF BLENHEIM, ONTARIO, CANADA.

HOLDER FOR DENTAL FLOSS.

Application filed February 27, 1922. Serial No. 539,692.

To all whom it may concern:

Be it known that I, ELDON W. EBY, of the town of Blenheim, in the county of Kent, Province of Ontario, Canada, a subject of the King of Great Britain, have invented certain new and useful Improvements in Holders for Dental Floss, of which the following is a specification.

This invention relates to holders adapted for conveniently holding dental floss which is used for removing foreign matter from between the teeth and my object is to devise a serviceable holder which will firmly hold a short length of floss in position for use.

I attain my object by means of the constructions hereinafter described and illustrated in the accompanying drawings in which—

Fig. 1 is a side elevation of my improved holder, partly broken away, to show the interior of the receptacle;

Fig. 2 an end elevation of the same;

Fig. 3 a side elevation showing the holder ready for use;

Fig. 4 a plan view of Fig. 1;

Fig. 5 a side elevation of my holder showing a modification of the clamping means partly retracted;

Fig. 6 a longitudinal section; and

Fig. 7 a plan view of Fig. 5.

In the drawings like numerals of reference indicate corresponding parts in the different figures.

The floss holder includes a receptacle 1 to which are secured a pair of suitably spaced similar arms 2 extending therefrom. On each of these arms 2 is suitably guided a spring pressed arm 3, the outer ends of these arms being adapted to engage the outer ends of the arms 2 to form clamps for gripping the floss as hereinafter described.

In one side of the receptacle 1 is formed an opening 5 through which a spool or bobbin 6 of dental floss may be placed on a pin 7 carried by the opposite side of the receptacle. A cover plate 22 pivotally connected to the receptacle at one side of the opening is provided with a projection at the other side adapted to engage in an indentation 20 formed in the receptacle. The free end of the floss is led through a slot 8 formed in the side of the receptacle and opening into the opening 5, and is then guided by means of 55 the guides 9 and 10, secured to one of the arms 2, to a transverse groove 11 formed

adjacent the outer end of the arm 2. The floss is strung across from this groove, when the spring pressed arms 3 are retracted, to a groove 12 formed in the other arm 2. These 60 grooves permit the floss to be positioned in the same plane as the spring pressed arms 3 so that the floss lying between each arm 2 and its adjacent arm 3 will be clamped tightly when the arms 3 are released. 65

It will be noted that the arms 3 engage the opposed sides of the arms 2 so that the former may slide longitudinally on the latter and that guides 13 secured on the latter receive the slideable arms 3 to prevent lateral 70 displacement of the arms 3. The inner ends of the arms 3 are connected to a slideable member 14, the underside of which is engaged by the compression spring or springs 15 which are suitably carried within the receptacle 1. The receptacle is formed with an open top adapted to receive the slideable member 14 when the latter is pressed against the action of the springs 15. 75

The arrangement of forming the clamps 80 for gripping the floss, shown in Figs. 1 to 4, is as follows. The opposed sides of the arms 2 are formed with inwardly directed tapered ends and the outer ends of the slideable arms 3 are correspondingly shaped to normally 85 engage the tapered ends. This is accomplished most satisfactorily by bending each set of adjacent arms 2 and 3 inwardly. In the upper ends of the arms 3 are formed notches 16 adapted to receive the floss to 90 prevent it sliding laterally on the arms when the floss is being used. To ensure the floss being retained in the notches 16, I provide the clips 21 suitably carried on the outer ends of the arms 3 underneath which 95 the floss is readily pressed.

The preferred form of clamp is shown in Figs. 5 to 7. In this construction the slideable arms 3 are provided with wedge shaped outer ends adapted to normally engage the 100 adjacent tapered surfaces 17 formed on the lugs 18 which are formed on or secured to the outer ends of the arms 2. In this construction the floss passes across the outer ends of the slideable arms 3 through notches 16^b formed therein, and through notches 16^a formed in the opposed sides of the lugs 18. These notches are used for the same purposes as the notches 16 hereinbefore described. 105

To present a fresh piece of floss between the spaced arms, the arms 3 are disengaged 110

from the ends of the arms 2 by pressing the member 14 inwardly, relative to the receptacle, against the action of the springs 15 and then pulling the free end of the floss 5 through the grooves 11 and 12, and then releasing the member 14 to grip the ends of the fresh piece of floss, as hereinbefore described. The used floss is then cut off by means of a cutting edge 19 formed on one 10 of the guides 18.

It is evident that with either of the clamping constructions hereinbefore described that if the floss is held from sagging when 15 strung between the arms 2 that on release 15 of the member 14 the arms 3 will jam the floss between them and their co-operating arms 2, and at the same time will stretch the floss so that it will be held taut.

What I claim as my invention is:

20 1. A dental floss holder including a pair of spaced arms; a second pair of arms mounted to slide longitudinally on the first mentioned arms and adapted to co-operate with the outer ends of the first mentioned 25 arms to form clamps to engage opposite ends of a length of floss; and yielding means tending to press the movable arms to their floss engaging position.

2. A dental floss holder including a pair 30 of spaced arms provided with tapered surfaces at their outer ends; a second pair of arms slidably mounted on the first mentioned arms and having their outer ends correspondingly shaped to co-operate with the 35 outer ends of the first mentioned arms to form wedges to clamp opposite ends of a length of floss; and yielding means tending to press the movable arms to their floss engaging position.

40 3. A dental floss holder including a pair of spaced arms provided with inwardly directed tapered surfaces at their outer ends; a second pair of arms slidably mounted on the first mentioned arms and having their 45 outer ends correspondingly shaped to co-operate with the outer ends of the first mentioned arms to form wedges to clamp opposite ends of a length of floss; and yielding means tending to press the movable arms 50 to their floss engaging position.

4. A dental floss holder including a pair of spaced arms provided with tapered surfaces at their outer ends, each arm being provided with a groove; a second pair of 55 arms slidably mounted on the first mentioned arms and having their outer ends correspondingly shaped to co-operate with the outer ends of the first mentioned arms to form wedges to clamp opposite ends of a 60 length of floss, the grooves being adapted to position the floss in the same plane as the movable arms; and yielding means tending to press the movable arms to their floss engaging position.

65 5. A dental floss holder comprising a floss

carrying receptacle having a pair of spaced arms extending therefrom, the floss being suitably carried along one of the arms and strung across to the other arm; a second pair of arms mounted to slide longitudinally on the first mentioned arms and adapted to co-operate with the outer ends of the first mentioned arms to form clamps to engage the portions of the floss lying between the co-operating ends of the arms; 75 and yielding means tending to press the movable arms to their floss engaging position.

6. A dental floss holder comprising a floss carrying receptacle having a pair of spaced 80 arms extending therefrom, each arm being provided with a tapered surface and a groove at its outer end; a second pair of arms slidably mounted on the first mentioned arms and having tapered surfaces 85 formed on their outer ends to co-operate with the tapered surfaces of the first mentioned arms to form wedge clamps, the grooves being adapted to receive the floss when it is strung across from one arm to 90 the other and position it in the same plane as the movable arms so that the latter will jam the portions of the floss lying between the co-operating outer ends of the arms; and yielding means tending to press the 95 movable arms to their floss engaging position.

7. A dental floss holder comprising a floss carrying receptacle having a pair of spaced arms extending therefrom, and provided 100 with an outlet opening for the floss; each arm being provided with a tapered surface and a groove at its outer end; floss guides carried by one of the arms, one guide being located adjacent the outlet opening and a 105 second guide adjacent the groove; a second pair of arms slidably mounted on the first mentioned arms and having tapered surfaces formed on their outer ends to co-operate with the tapered surfaces of the first 110 mentioned arms to form wedge clamps, the grooves being adapted to position the floss in the same plane as the movable arms so that the latter will jam the portions of the floss lying between the co-operating outer 115 ends of the arms; and yielding means tending to press the movable arms to their floss engaging position.

8. A dental floss holder comprising a pair of spaced arms, each arm being provided 120 with a tapered surface and a groove at its outer end; means for carrying a supply of floss; a floss guide carried by one of the arms and located adjacent the groove; a second pair of arms slidably mounted on the 125 first mentioned arms and having tapered surfaces formed on their outer ends to co-operate with the tapered surfaces of the first mentioned arms to form wedge clamps, the grooves being adapted to position the floss 130

in the same plane as the movable arms so that the latter will jam the portions of the floss lying between the co-operating outer ends of the arms; and yielding means tending to press the movable arms to their floss engaging position.

9. A dental floss holder constructed as set forth in claim 8 in which means are provided for cutting off the used end of the floss.

10. A dental floss holder comprising a receptacle having a pair of spaced arms extending therefrom and provided with an opening adapted to receive a spool of floss and having a slot formed therein communicating with the opening, each arm being provided with a tapered surface and a groove at its outer end; a pin carried within the receptacle for carrying the spool; floss guides carried by one of the arms, one

guide being located adjacent the slot, and a second guide adjacent the groove; a second pair of arms slidably mounted on the first mentioned arms and having tapered surfaces formed on their outer ends to co-operate with the tapered surfaces of the first mentioned arms to form wedge clamps, the grooves being adapted to position the floss in the same plane as the movable arms so that the latter will jam the portions of the floss lying between the co-operating outer ends of the arms; and yielding means tending to press the movable arms to their floss engaging position.

Signed at Blenheim, Ontario, this 14th day of February, 1922.
